(57) **CLAIM**

The ornamental design for a device to close wounds, as shown and described.

DESCRIPTION

FIG. 1 is a perspective view of a device to close wounds, wherein broken lines are on the middle web of the device; FIG. 2 is a first side elevational view of the device in FIG. 1; the opposite side view being a mirror image; FIG. 3 is a third side elevational view of the device in FIG. 1; the opposite side view being a mirror image; FIG. 4 is a top view of the device in FIG. 1; and, FIG. 5 is a bottom view of the device in FIG. 1. The broken lines represent portions of the structure that form no part of the claim.
